J. A. CREPEAU.
BOILER TUBE SCRAPER.
APPLICATION FILED OCT. 29, 1915.

1,193,361.

Patented Aug. 1, 1916.

UNITED STATES PATENT OFFICE.

JOSEPH ARTHUR CREPEAU, OF SOREL, QUEBEC, CANADA.

BOILER-TUBE SCRAPER.

1,193,361.

Specification of Letters Patent. Patented Aug. 1, 1916.

Application filed October 29, 1915. Serial No. 58,722.

To all whom it may concern:

Be it known that I, JOSEPH A. CREPEAU, a subject of the King of Great Britain residing at Sorel, in the Province of Quebec and Dominion of Canada, have invented 5 certain new and useful Improvements in Boiler-Tube Scrapers; and I do hereby declare the following to be a full, clear, and exact description of the invention, such as 10 will enable others skilled in the art to which it appertains to make and use the same.

The invention relates to improvements in boiler tube scrapers.

The object of the present invention is to 15 improve the construction of boiler tube scrapers and to provide a simple, practical and comparatively inexpensive device of this character designed to be operated by electric, steam or compressed air power and 20 equipped with means for introducing jets of air into the boiler tube in rear of the tool to blow the dust away as soon as it is scraped from the tube.

With these and other objects in view the 25 invention consists in the construction and novel combination and arrangement of parts hereinafter fully described, illustrated in the accompanying drawings and pointed out in the claim hereto appended, it being 30 understood that various changes in the form, proportion and minor details of construction may be resorted to without departing from the spirit or sacrificing any of the advantages of the invention.

35 In the drawing Figure 1 is a side elevation of a boiler tube scraper constructed in accordance with this invention, Fig. 2 is a central longitudinal sectional view of the same, Fig. 3 is a transverse sectional view 40 on the line 3—3 of Fig. 2, Fig. 4 is a transverse sectional view on the line 4—4 of Fig. 2, Fig. 5 is an end elevation.

Like numerals of reference designate corresponding parts in the several figures of 45 the accompanying drawing.

In the accompanying drawing in which is illustrated the preferred embodiment of the invention, the boiler tube scraper comprises in its construction a tool 1, a holder 2, and 50 a connecting tube or pipe 3. The tool consists of a body 4 yieldably mounted radially adjustable blades 5. The body 4 consists of an inner exteriorly threaded tubular portion 6 and a solid outer cylindrical portion 7 55 provided with longitudinal grooves receiving the radially movable blades 5 which are

forced outwardly by springs 9 mounted in recesses 10 in the inner edges of the blades and arranged within the said grooves 8. The blades which have beveled outer cutting edges 11 are provided with reduced terminal portions 12 extending beneath inner and outer rings 13 secured on the cylindrical portion 7 in annular recesses 14 thereof by screws 15 which may be countersunk in the 65 rings as shown in Fig. 5 or otherwise arranged.

The body of the tool is provided at its intermediate portion 16 with an exterior annular groove 17 and a series of radially arranged jet apertures 18 communicating at their inner ends with the interior of the tubular portion 6 and adapted to discharge jets of air into the boiler tube operated on at a point in rear of the scraper blades to 75 blow the dust from the boiler tube as soon as it is scraped off by the said blades 5.

The tubular stem or shank portion 6 of the body 4 of the tool screws into the outer end of the connecting pipe 3 and the inner 80 or rear end of the connection pipe is threaded into a socket formed by a sleeve 19 which constitutes the front or outer portion of the holder 2. The holder is provided with a shank 20 having a head 21 circular in cross 85 section and reduced at 22 and 23 to receive the said sleeve 19 and a ring 24 of a handle 25. The reduced portion is threaded to receive the interiorly threaded sleeve 19 which abuts against the shoulder 26 formed by the 90 second reduction. The reduced portion 23 is provided with a series of apertures 27 for the passage of air and the said apertures are covered by the rings or bands 24 and are adapted to communicate with a longitudinal 95 opening or bore 28 of the handle 25 which is counterbored at the outer portion at 29 to receive a pipe or tube 30 for connection with any suitable source of compressed air. The shank 20 is designed to be mounted in a 100 pneumatic drilling machine but it may be operated by any suitable power. The blades are rounded at their outer corners at the terminals of the cutting edges at 31 to enable the tool to be readily introduced into and removed from a boiler tube and it is adapted 105 to be entirely passed through the same and operated in the ordinary manner, the tool being rotated by the drilling machine or other power and the blades engaging the interior of the boiler tube are operated for scraping the dust and other accumulation

110

therefrom. When the air is turned on at the pipe 30 it passes through the hollow handle or member 25 and enters the recess 32 through the aperture 27. The air then passes through the connecting pipe and enters the tubular portion of the tool body 4 and is discharged at the exterior annular groove 17 through the jet apertures 18.

What is claimed is:

10. A boiler scraper including a tool comprising a cylindrical body provided with longitudinal grooves and having reduced portions at the ends of the grooves, blades operating in the grooves and provided with
- 15 spaced radially arranged rectangular recesses at their inner edges and having re-

duced terminal portions, spaced coiled springs located in the recesses and bearing against the bottom walls of the said grooves for urging the blades outwardly and rings 20 mounted on the reduced portions of the said body portion and arranged to be engaged by the terminal projecting portions of the blades to limit the outward movement thereof.

25 In testimony whereof I affix my signature in presence of two witnesses.

JOSEPH ARTHUR CREPEAU.
